UNITED STATES PATENT OFFICE.

CARL A. WENDELL, OF JOLIET, ILLINOIS.

DRIER.

1,218,024.

Specification of Letters Patent. Patented Mar. 6, 1917.

Application filed June 9, 1916. Serial No. 102,671.

To all whom it may concern:

Be it known that I, CARL A. WENDELL, a citizen of the United States, residing at Joliet, in the county of Will and State of Illinois, have invented a certain new and useful Improvement in Driers, of which the following is a specification.

My invention relates to improvements in centrifugal drying machines adapted for the purpose of extracting moisture from material and has for one object to provide a centrifugal drying machine wherein the feed is gradually fed into the machine and gradually discharged therefrom, without interfering with the balance of the machine and without any sudden strains or shock or jars or jolts, and without interfering with the smooth running qualities of the apparatus. Another object is to provide a device wherein the time during which the material to be dried remains in the machine may be closely and accurately controlled by the operator without interfering with the feed or discharge when it takes place, without making the feed or discharge irregular or unsteady and without throwing the machine out of balance and without stopping the machine. Other objects will appear from time to time in my specification.

My invention is illustrated more or less diagrammatically in the accompanying drawings, wherein—

Figure 1 is a vertical section and Fig. 2 a section along the line 2—2 of Fig. 1;

Fig. 3 a detail section along the line 3—3 of Fig. 1.

Like parts are indicated by like characters in all of the figures.

A, A is a supporting base. Projecting upwardly from it is a housing and support A¹ A¹. This housing and support carries a cover or closure A², and a bracket A³, together with a bracket A⁴. The shaft A⁵ is rotatably mounted in the bearings A⁶ A⁷ on the brackets A⁸ A⁹, and is adapted to be driven from any suitable source of power

applied through the pulley A⁸. The shaft A⁵ carries rigidly mounted thereon, miter gears A⁹ A¹⁰, in a housing A¹¹.

The vertical shaft B is rotatably mounted in a bearing B¹ supported on the cover A² at one end, and at the other end it is rotatably mounted in a bearing B² supported by a bracket B³. B⁴ is a miter gear rigidly mounted on the shaft B, and in mesh with the miter gear A¹⁰ so that it is positively driven from the shaft A⁵. B⁵ is a sleeve rotatably mounted on the shaft B, held against longitudinal movement therealong by the shoulder B⁶. This sleeve carries a miter gear B⁷ in mesh with the miter gear A⁹. The relative sizes of the different miter gears are such that while both the shaft and the sleeve are driven from the horizontal driving shaft, they are driven at different angular velocities. The sleeve B⁵ is supported on the shaft B by means of the anti-friction bearing sleeves B⁸ B⁹. B¹⁰ is a spider carried by the sleeve B⁵ adjacent its lower end. This spider takes the form of a substantially continuous, generally conical disk which forms the movable or rotated top of the separating or drying chamber.

C is a conical screen made up of a series of separate sections as indicated, supported by and downwardly depending from the spider B¹⁰. The inclination of this screen being much sharper than the inclination of the spider. This screen is supported in a frame C¹ which frame carries a flange C² extending upwardly toward the under side of the periphery of the spider B¹⁰ so as to form a series of discharge chutes or spouts C³ through which the moisture, which first passes through the screen, may be discharged. These spouts are divided up, one from another, by a series of walls C⁴, forming a part of the frame C¹. These spouts discharge into a circular gutter C⁵ mounted on the inner wall of the housing A¹. This gutter discharges finally through a pipe C⁶ to any suitable water discharge point not here specifically illustrated. It will be noted

that the spider, the frame, the screen and the discharge spouts all rotate in unison with the supporting sleeve at a speed different from the rotation of the central shaft.

5 D is a hub mounted for rotation on the central shaft and provided with arms D¹, which arms extend out to and are attached to the frame C¹ so that this hub and arms also rotate in unison with the sleeve and has 10 a bearing member D² interposed between the hub and the shaft. D³ D³ are a series of normally horizontal trap doors, which together with a conical floor D⁴ form a continuous floor for the drying chamber, which floor ex- 15 tends clear out to the screen. Each of these trap doors D³ is separately pivoted to the floor as indicated and makes a firm joint with the screen. They are each of them pro- 20 vided with a weighted arm D⁵ projecting downwardly and provided at its end with a cam engaging roller D⁶. The proportion and arrangement of trap doors and arm is such that when the device is in operation, the weight of the arm will more than counter- 25 balance the weight of the screen and any load carried by it. The weight of the trap door and any load carried by it will hold the trap door in a closed position so that nothing may pass through between the trap door 30 and the screen.

E is a supply hopper fed through an opening E¹ in the cover A² from a chute E² which is adapted to be connected or disconnected with a suitable source of supply by any con- 35 trol means not here indicated. This hopper discharges down through the central portion of the spider B¹⁰ onto a feed plate E³. This feed plate is keyed to the shaft B and is made up of two separate feed nozzles E⁴ E⁴, 40 discharging tangentially and having inclined discharge mouths E⁵ directed toward the screen. E⁶ is a conical cover for the nozzle to assist in directing the material toward the screen. E⁷ is an apron attached to 45 the hopper E and extending down over the spider B¹⁰ to protect the parts and guide and deflect any material discharged from the machine down toward the water chute.

F is a hub keyed to the shaft B. It carries 50 a spider F¹ which spider supports a cam ring F². This cam ring is in the path of the roller D⁶. The hub is free to slide along but cannot rotate with respect to the shaft. It is supported on a roller bearing F³ which 55 roller bearing rests on a sleeve F⁴ held against rotation by the pin F⁵ and free to slide along the shaft. F⁶ is a nut free to rotate with respect to the shaft in screw- threaded engagement with the sleeve F⁴ but held against longitudinal movement by the 60 collar F⁷. This nut is provided on the outside with a worm gear F⁸ in mesh with a worm F⁹ which worm is manipulated by means of a hand wheel F¹⁰ through a shaft

F¹¹ so as to raise and lower the hub and raise and lower the cam with respect to the shaft.

It will be evident that while I have shown in my drawings an operative device still many changes might be made both in size, shape and arrangement of parts without departing materially from the spirit of my invention. I wish therefore that my drawings be regarded as in a sense diagrammatic.

The use and operation of my invention are as follows:

With the parts in the position shown, the power is applied and the centrifugal machine brought up to speed. The shaft travels at one speed, the sleeve at another so that the drying chamber with its screen outer wall rotates more rapidly than the feed spout and the cam, and feed spout and cam rotating at the same speed.

Under ordinary circumstances my apparatus is so timed that with the parts operating in their normal, natural way the material always stays in the machine long enough to be properly dried. It happens, however, that sometimes material must be dried which does not respond with rapidity to the drying treatment. For instance, if I wish to draw off the liquor from finely crystallized sugar or if I am expelling oil from ground or pulverized oil containing vegetable products; the normal time given is not sufficient to expel the liquid and for this reason I provide means for interrupting at the will of the operator, the operation of the material discharge so that the material may be kept in the machine a greater length of time.

My arrangement, wherein without stopping the machine I merely drop down the trap door opening cam or throw out of operation the means for opening the normally closed discharge way, can be operated at any time by the operator. When the discharge mechanism is thrown out of operation, the material stays in the machine indefinitely and when the operator throws the discharge mechanism back into operation, the discharge goes on successive sections of the dried material and being discharged one after another goes on just as if the discharge had never been interrupted.

In using my device, therefore, the operator will start the machine and bring it up to speed. He will then disengage the discharge operating mechanism to permit material to run in until the rotor is filled with the material being dried. He will then stop the feed of the material to the drier until the material therein has all been dried. He will then recommence the feed of material to the drier and discharge of material from the drier until the drier is filled with fresh material and all of the dried material

has been discharged. He will then again cut off the supply both to the drier and from the drier. This process can be continued indefinitely without changing in any way 5 the operation of the drier and without necessitating any stopping or starting of the machine.

I claim:

1. In a centrifugal drier, the combination 10 of a frame, a pair of horizontal rotatable differentially geared members, one of said members being in the form of a delivery spout, the other of said members acting as a separating member whereby moisture is projected from the material by centrifugal action, a screen carried by said last named member, said screen being mounted at an angle to the vertical, and a trap mounted in said last named member, means for opening 15 said trap whereby material forced against said screen by the centrifugal force is by the same force projected outwardly through said trap, and means independent of the rotation of the spout and receptacle 20 for interrupting the operation of such trap opening means.

2. In a centrifugal drying machine the combination of a frame, a feed spout, a material receptacle containing a screen through 30 which the water is expelled by centrifugal force and a normally closed discharge way, means for rotating the spout and the receptacle differentially, and means for intermittently opening the discharge way responsive 35 to the relative rotation of the spout and receptacle, and means independent of the rotation of the spout and receptacle for interrupting the operation of the discharge way opening means.

3. In a centrifugal drying machine the combination of a frame, a feed spout, a material receptacle containing a screen through 40 which the water is expelled by centrifugal force and a normally closed discharge way, means for continuously rotating the spout and the receptacle differentially, means for intermittently opening the discharge way responsive 45 to the relative rotation of spout and receptacle, and means independent of the rotation of the spout and receptacle for interrupting the operation of the discharge way opening means.

4. In a centrifugal drying machine the combination of a frame, a feed spout, a material receptacle containing a screen inclined 55 at an angle to the axis of rotation and through which the water is expelled by centrifugal force and a normally closed discharge way, means for rotating the spout and the receptacle differentially, means for intermittently opening the discharge way responsive 60 to the relative rotation of spout and receptacle, and means independent of the rotation of the spout and receptacle for interrupting the operation of the discharge way opening means.

interrupting the operation of the discharge 65 way opening means.

5. In a centrifugal drying machine the combination of a frame, a feed spout, a material receptacle containing a screen inclined at an angle to the axis of rotation and through which the water is expelled by centrifugal force and a normally closed discharge way, means for continuously rotating the spout and the receptacle differentially, means for intermittently opening the discharge way responsive 70 to the relative rotation of spout and receptacle, and means independent of the rotation of the spout and receptacle for interrupting the operation of the discharge way opening means.

6. In a centrifugal drying machine the combination of a frame, a feed spout, a material receptacle comprising a series of sections each containing a screen through which the water is expelled by centrifugal force 85 and a normally closed discharge way, means for rotating the spout and the receptacle differentially, means for intermittently opening the discharge way responsive to the relative rotation of spout and receptacle, and means independent of the rotation of the spout and receptacle for interrupting the operation of the discharge way opening means.

7. In a centrifugal drying machine the combination of a frame, a feed spout, a material receptacle comprising a series of sections each containing a screen through which the water is expelled by centrifugal force and a normally closed discharge way, means for continuously rotating the spout and the receptacle differentially, means for intermittently opening the discharge way responsive 90 to the relative rotation of spout and receptacle, and means independent of the rotation of the spout and receptacle for interrupting the operation of the discharge way opening means.

8. In a centrifugal drying machine the combination of a frame, a feed spout, a material receptacle comprising a series of sections each containing a screen inclined at an angle to the axis of rotation and through which the water is expelled by centrifugal force and a normally closed discharge way, means for rotating the spout and the receptacle differentially, means for intermittently opening the discharge way responsive 110 to the relative rotation of spout and receptacle, and means independent of the rotation of the spout and receptacle for interrupting the operation of the discharge way opening means.

9. In a centrifugal drying machine the combination of a frame, a feed spout, a material receptacle comprising a series of sections each containing a screen inclined at an angle to the axis of rotation and through which the water is expelled by centrifugal force and a normally closed discharge way,

means for continuously rotating the spout and the receptacle differentially, means for intermittently opening the discharge way responsive to the relative rotation of spout 5 and receptacle, and means independent of the rotation of the spout and receptacle for interrupting the operation of the discharge way opening means.

10. In a centrifugal drying machine the combination of a feed spout and a ring shaped material receptacle to which the spout discharges from within, means for rotating them continuously differentially in the same direction, means for discharging successive dried sections of the material from the ring receptacle in advance of the spout responsive to the relative rotation of spout 15 and receptacle, and means independent of the rotation of the spout and receptacle for interrupting the operation of the dried material discharge.

11. A centrifugal drier comprising a rotating drying chamber, means for feeding material to it, a conical perforate wall forming the outer periphery of the drying chamber, a series of pivoted trap doors forming a portion of the bottom floor of the drying chamber, these doors normally closed, means 20 rotating in unison with the feed supply means for opening such doors intermittently to permit discharge of dried material and means controlled by the operator and independent of the operation of the feed mechanism and the rotation of the drying chamber 25 for interrupting the operation of such trap door opening mechanisms.

12. A centrifugal drier comprising a drying chamber and means for rotating it, a se-

ries of trap doors in the bottom of the chamber for the discharge of the dried material, 40 a feed spout discharging into the chamber and means for rotating it at a different velocity than the chamber, and means operated and rotated in unison with the feed spout for successively opening intermittently 45 the trap doors and means controlled by the operator and independent of the rotation of the parts for arresting such operation.

13. A centrifugal drier comprising a drying chamber and means for rotating it, a 50 series of trap doors in the bottom of the chamber for the discharge of the dried material, a feed spout discharging into the chamber and means for rotating it at a different velocity than the chamber, and means 55 operated and rotated in unison with the feed spout for successively opening intermittently the trap doors and means controlled by the operator and independent of the rotation of the parts for arresting such operation. 60

In testimony whereof, I affix my signature 70 in the presence of two witnesses this 9th day of May 1916.

CARL A. WENDELL.
